REVOLVER HOLSTER

John Emmett Berns, Bremerton, Wash.

Application September 6, 1932, Serial No. 631,745

3 Claims. (Cl. 224—2)

My invention relates to a revolver holster. More particularly, my invention relates to a holster for the reception of a revolver, whereby the revolver may be withdrawn by the user and placed in a shooting position with maximum speed. Another object of my invention is to provide a revolver holster which will secure and retain the revolver in the holster without the holster coming in contact with the sights of the revolver.

In connection with the protection of the sights of a revolver, it should be kept in mind that when revolvers are used for target practice, the sights are smoked or otherwise temporarily blackened, so that the sights will clearly contrast with a white background. It has been heretofore the custom of target shooters to blacken the sights of their revolver, and to carry such sight blackened revolver in their hand without replacing the same in the holster, so that the blackening on the sights would not be worn off by contact with the holster before the revolver was used for shooting. In my invention the revolver may be placed in the holster with the sights blackened to suit the individual shooter, and the sights will be protected against wearing and rubbing while the revolver is in the holster.

Ordinarily, experts with revolvers will color the sights on their revolver in such a way that the sights will contrast with the color of the background against which they are shooting, thus making the sights more clearly definable. This is not confined to target shooters who darken their sights when shooting against a white background, and when other color backgrounds obtain, very often the marksmen will see fit to place ivory tips, gold tips, or other coloring on the sights, so that a contrast is had between the sights and the background, permitting the highest degree of accuracy in shooting. In the interest of continued accurate shooting, it is necessary to protect the sights from wear, so that the sights are not diminished in size or changed in color, and further, so that the sights do not become shiny and brilliant.

A further object of my invention is to provide a holster for a revolver, so designed as to prevent vertical movement of the revolver without the use of the ordinary straps. Heretofore holsters have been provided where the revolver is inserted from the upper end of the holster and moved downwardly therein. When the revolver was worn, in such a holster, by men who were riding horseback, or in similar position where an up and down movement of their body was had,

the tendency of the revolver was to likewise move in a vertical direction, and at times the revolver would fall out of the holster. To prevent this, many of the policemen of today wear straps over the upper side of their revolver, so that the same cannot accidentally leave the holster. This, of course, prevents rapid access to the revolver. At times when such rapid access to the revolver might be extremely urgent, the revolver is not accessible. In my device the revolver is held against vertical movement, and may be speedily and rapidly withdrawn by a forward horizontal movement of the butt end of the revolver, and thereafter the revolver can be readily moved into shooting position by a simple twist of the wrist.

The above mentioned general objects of my invention, together with others inherent in the same, are attained by the device, illustrated in the following drawing, the same being preferred exemplary forms of embodiment of my invention, throughout which drawing like reference numerals indicate like parts:

Figure 1 is a view in perspective of my holster with a revolver inserted therein, showing the same adapted to the belt of a wearer, only the central portion of the wearer being indicated.

Fig. 2 is a view similar to Figure 1, with the revolver tipped slightly forward and being removed from the holster.

Fig. 3 is a vertical section of the holster embodying my invention.

Fig. 4 is a section substantially on line 4—4 of Fig. 3.

Fig. 5 is a view substantially on line 5—5 of Fig. 3.

Fig. 6 is a modified form of the end retaining member shown in Fig. 5.

Fig. 7 is a view in perspective, with parts broken away, showing the means to connect the holster, embodying my invention, to a strap or belt of the wearer.

Referring to the drawing, 10 indicates a firearm of the type generally known as a revolver. My holster 11 is preferably provided with an overlapping strap 12, positioned upon the upper rear side thereof, providing an opening 14 between the overlapping strap and the holster 11 for the insertion therein of a belt 13 to be worn by the wearer. The belt 13 of the wearer is preferably of suitable size, so that after the same is inserted through the opening 14 between the overlapping strap 12 and the holster 11, swinging movement of the holster and sliding movement of the same as respects the belt 13 is prevented. This is readily accomplished by providing a belt 13, which

will snugly fit in the opening 14. The holster 11 is provided with an open portion 15 upon the normal forward portion of the holster and upon part of the normal upper portion of the holster, 5 and a curved portion 16 is provided, with a contour similar to the contour of the trigger guard 17 of the revolver. A spring clamp 18 of substantially U shape is positioned within the holster, so that the curved portion 19 of the spring clamp 10 will embrace the cylinder 20 of the revolver. This spring clamp 18 may be secured to the holster by means of retaining members 29 which are sewed or otherwise secured to the sides of the holster over the spring clamp 18, thereby forming pockets 15 for the retention of such spring clamp. These retaining members may be of leather or of like soft material and cover the spring 18 at the location of contact with the cylinder 20 of the revolver, thereby protecting the revolver from contact with the metal spring clamp 18. The lower portion 21 of the holster has a stop member 22 provided within the holster at the forward edge of the portion 21 and cooperates to form a recess 27 for the reception of the muzzle end of the revolver barrel 26. The form shown in Fig. 5 is adapted to receive the muzzle end of a revolver of the type shown where the front sight 23 is somewhat back from the muzzle end of the revolver. In the event that the front sight 23 of 30 the revolver is substantially flush with the end of the barrel 26, the end retaining member shown in Fig. 6 should be preferably used. The end retaining member shown in Fig. 6 is made in a similar manner, and is provided with a recess 24 35 similar to the recess 27 of the end retaining member shown in Fig. 5. In addition to the recess 24, there is provided in the stop member 28, shown in Fig. 6, an aperture or slot 25 which cooperates with recess 24 to provide an end receiving member 40 for the muzzle end of such a revolver.

In the use of the holster embodying my invention, the revolver 10 is inserted into the holster by first thrusting the muzzle end of the barrel portion of the revolver, indicated generally by 45 numeral 26, through the open front or the open top portion of the holster and placing the end of the barrel in the recess 27 in the bottom of the holster. The revolver is indicated in this position in Fig. 2 of the drawing. The upper portion of the revolver is then moved backward so that the trigger guard 17 will be positioned under and against the curved portion 16 of the holster. In moving this upper portion of the revolver in a rearward direction, the two parts of the spring 50 member 18 will be separated and permit the revolver to be positioned in the holster. After the revolver is so positioned in the holster, the revolver will be retained in the holster against vertical movement by the curved portion 16 of the holster 55 which engages the trigger guard and thereby holds the muzzle end of the revolver barrel firmly in place in the recess 27. The spring 18 surrounds the cylinder 20 of the revolver and releasably holds the upper portion of the revolver against horizontal movement. To remove the revolver 60 from the holster, it is only necessary that the wearer move the butt portion of the revolver forward in a horizontal direction, and then twist his wrist to place the revolver in firing position. The 65 forward movement of the butt portion of the revolver is resisted by the action of spring member 18. This spring member may be provided with a suitable tension, sufficient to retain the revolver against accidental dislodgment, and yet not provide an excessive pressure, which the wearer must 70

75

overcome, in drawing the revolver from the holster.

The edges of the holster forming therebetween the open portion 15, through which the revolver is inserted into the holster and withdrawn therefrom, are sufficiently spaced apart and sufficiently extended so that the front sight 23 and the rear sight 30 of the revolver cannot touch such edge portions, and so that these edge portions form a guard preventing external objects touching such sights. 10

In the ordinary holster, which has heretofore been used, the movements to bring the revolver into action are substantially that the wearer must first lift the revolver a considerable distance, and then turn the revolver to a substantially horizontal position. In my invention it is only necessary for the wearer to move the butt portion of the revolver slightly forward, and then, in practically the same motion, to turn 20 the revolver to a horizontal position for firing. It should be realized that the average length of revolvers in common use is approximately seven to twelve inches, and therefore, the wearer must lift the revolver approximately this distance, in using the holsters heretofore in common use, before he can turn his wrist and place the revolver into a firing position. The difference in the speed with which a revolver may be withdrawn from my holster and other holsters 30 is determined by this upward movement which is necessary in the use of an ordinary holster, but is entirely eliminated when my holster is used. 25

Besides providing a holster whereby a quicker draw of the revolver may be had, it should be 35 noted that in my holster, the curved portion 16 prevents the revolver from being raised vertically in the holster, as such curved portion partially surrounds the trigger guard 17. This feature adds additional protection to the wearer of 40 the holster. To remove the revolver from the holster, it is necessary that a slight forward movement of the butt portion of the revolver be had, and then that the revolver be twisted upward, so that the barrel 26 is moved to a 45 horizontal position. In the event that someone should attack and attempt to disarm a wearer from the rear, the revolver cannot be drawn backwardly, or upwardly, but the butt portion must first be tipped forward. Such move from 50 the back to disarm a wearer will take considerable more time than would be necessary to withdraw a revolver from an ordinary holster, and thereby adds additional protection to the wearer, so that he may not be easily disarmed by 55 artifice from the rear. Furthermore, in the event that a wearer of an ordinary holster is disarmed from the rear, the revolver is pointed at the wearer just after such disarming, while in my holster the revolver will be pointed forward- 60 ly and not at the wearer.

In the event that extremely long revolvers are used, the same may be withdrawn from my holster, and the great loss of time, which is incident to the withdrawing of such revolvers from 65 ordinary holsters, is eliminated. To prevent such loss of time in the withdrawing of long barreled revolvers from holsters, it has been the practice of men experienced in the use of firearms to "saw off" the barrel of such revolvers and thereby minimize the up lift to withdraw the revolver from the holster. It is clear from the operation of my holster that the speed with which the revolver may be withdrawn from the holster is not determined by the length of the barrel, and 70 75

therefore that such "sawing off" process is not necessary to obtain a speedy draw, and clearly the necessity for using "sawed off" or short barreled revolvers, which are inherently less accurate than revolvers having longer barrels, is so overcome.

Obviously, changes may be made in the forms, dimensions, and arrangement of the parts of my invention, without departing from the principle thereof, the above setting forth only preferred forms of embodiment.

I claim:

1. A holster of the class described embodying a case member provided with an open slot in the front and upper portions thereof, through which a revolver may be inserted into the holster and withdrawn therefrom, the edges of the holster around said front slot extending forwardly to provide a guard for the sights of the revolver; a curved pocket in the upper rear portion of the holster to receive the upper rear curved part of the trigger guard member of a revolver; a revolver barrel end supporting member in the lower end portion of the holster; and a spring member positioned in the holster adapted to frictionally engage a revolver and to releasably hold said rear curved part of the trigger guard member of the revolver in said curved pocket of the holster, thereby frictionally retaining the revolver in said holster.

2. A holster of the class described embodying a case member provided with an open slot in the front and upper portions thereof, through which a revolver may be inserted into the holster and withdrawn therefrom, the free edges of the holster around said front slot extending forwardly

to provide a guard for the sights of the revolver; a curved pocket in the upper rear portion of the holster to receive the upper rear curved part of the trigger guard member of a revolver; a revolver barrel end supporting and retaining member in the lower end portion of the holster, said member having an aperture to receive the end of the barrel and a slot cooperating with said aperture to receive a sight on the revolver positioned flush with its end; and a spring member positioned in the holster adapted to frictionally engage a revolver and to releasably hold said rear curved part of the trigger guard member of the revolver in said curved pocket of the holster, thereby frictionally retaining the revolver in 15 said holster.

3. A holster of the class described embodying a case member provided with an open top and with an open slot in the front, said opening in the front extending from the top to the bottom 20 portion of the case member through which a revolver may be inserted into the holster and withdrawn therefrom, the edges of the holster around said front slot extending forwardly to provide a guard for the sights of the revolver; a 25 revolver barrel end supporting member in the lower end portion of the holster; and a spring member positioned in the case member adapted to frictionally engage the lateral portions only of a revolver, leaving a clear space for the sights 30 when the revolver is positioned in the case member, whereby the revolver may be carried in said case member with sights provided with colored matter and without loss of said colored matter by contact with the case member.

JOHN EMMETT BERNIS.
